CLAIM

The ornamental design for stud-mounted polycrystalline toothed diamond cutting blank, as shown and described.

DESCRIPTION

FIG. 1 is a front elevational view of the stud-mounted polycrystalline toothed diamond cutting blank showing my new design;

FIG. 2 is a left side elevational view the opposite view being a mirror image thereof;

FIG. 3 is a rear elevational view;

FIG. 4 is a top plan view; and

FIG. 5 is a bottom plan view.

FIG. 1

FIG. 2

FIG. 3

FIG. 4

FIG. 5
